(57) **CLAIM**

The ornamental design for an electrical connector, as shown and described.

DESCRIPTION

FIG. 1 is a perspective view of the front, top and right side of the electrical connector according to the first embodiment, showing our new design;

FIG. 2 is a perspective view of the front, bottom and right side thereof;

FIG. 3 is a perspective view of the rear, top and left side thereof;

FIG. 4 is a perspective view of the rear, bottom and left side thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom view thereof;

FIG. 11 is a perspective view of the front, top and right side of the electrical connector according to the second embodiment, showing our new design;

FIG. 12 is a perspective view of the front, bottom and right side thereof;

FIG. 13 is a perspective view of the rear, top and left side thereof;

FIG. 14 is a perspective view of the rear, bottom and left side thereof;

FIG. 15 is a front view thereof;

FIG. 16 is a rear view thereof;

FIG. 17 is a left side view thereof;

FIG. 18 is a right side view thereof;

(Continued)

FIG. 19 is a top plan view thereof; and,
 FIG. 20 is a bottom view thereof.
 The broken line showing of the electrical connector is for the
 purpose of illustrating portions of the electrical connector
 and forms no part of the claimed design.

1 Claim, 16 Drawing Sheets
